[57] CLAIM

The ornamental design for a nasal implant, as shown and described.

DESCRIPTION

FIG. 1 is a top, front, left end perspective view of a nasal implant, showing our new design;

FIG. 2 is a bottom, rear, right end perspective view thereof;

FIG. 3 is a front elevational view thereof, the rear elevational view being identical;

FIG. 4 is a top plan view thereof;

FIG. 5 is a bottom plan view thereof;

FIG. 6 is a left side elevational view thereof;

FIG. 7 is a right side elevational view thereof; and FIG. 8 is a top, front, left end perspective view of a second embodiment of the nasal implant;

FIG. 9 is a bottom, rear, right end perspective view thereof;

FIG. 10 is a front elevational view thereof, the rear elevational view being identical;

FIG. 11 is a top plan view thereof;

FIG. 12 is a bottom plan view thereof;

FIG. 13 is a left side elevational view thereof;

FIG. 14 is a right side elevational thereof;

FIG. 15 is a top, front, left end perspective view of a third embodiment of the nasal implant;

FIG. 16 is a bottom, rear, right end elevational view thereof;

FIG. 17 is a front elevational view thereof, the rear elevational view being identical;

FIG. 18 is a top plan view thereof;

FIG. 19 is a bottom plan view thereof;

FIG. 20 is a left side elevational view thereof;

FIG. 21 is a right side elevational view thereof;

FIG. 22 is a top, front, left end perspective view of a fourth embodiment of the nasal implant;

FIG. 23 is a bottom, rear, right end perspective view thereof;

FIG. 24 is a front elevational view thereof, the rear elevational view being identical;

FIG. 25 is a top plan view thereof;

FIG. 26 is a bottom plan view thereof;

FIG. 27 is a left side elevational view thereof; and

FIG. 28 is a right side elevational view thereof.
